UNITED STATES PATENT OFFICE.

LEE WARREN BARBER, OF CHICAGO, ILLINOIS, ASSIGNOR TO STANDARD CAR TRUCK COMPANY, OF CHICAGO, ILLINOIS, A CORPORATION OF NEW JERSEY.

CENTER-BEARING FOR RAILWAY-CARS.

1,128,743.

Specification of Letters Patent. Patented Feb. 16, 1915.

Application filed March 9, 1914. Serial No. 823,321.

To all whom it may concern:

Be it known that I, LEE WARREN BARBER, a citizen of the United States, residing at Chicago, in the county of Cook and State 5 of Illinois, have invented certain new and useful Improvements in Center-Bearings for Railway-Cars; and I do hereby declare the following to be a full, clear, and exact description of the invention, such as will 10 enable others skilled in the art to which it appertains to make and use the same.

My invention has for its object to provide an improved center bearing for railway cars, and to such ends, generally stated, 15 the invention consists of the novel devices and combinations of devices hereinafter described and defined in the claims.

In the accompanying drawings which illustrate the invention, like characters indicate like parts throughout the several views.

Referring to the drawings: Figure 1 is a view partly in vertical section and partly in elevation, and with some parts broken away, showing the improved center bearing; Fig. 2 is a bottom plan view of the hub portion of the upper bearing plate member, some parts being broken away; Fig. 3 is a perspective view showing a portion of a retaining ring used on the hub of the 25 upper bearing member; and Fig. 4 is a side elevation showing a thrust ring which is used in connection with the upper bearing member.

The lower bearing member 1 has an upper 35 turned sleeve-like hub 2, and the upper bearing member 3 is provided with a depending sleeve-like hub 4 that surrounds the said hub 2. The bearing members 1 and 3 are provided with opposing conical surfaces 40 on which are placed opposing outwardly flaring annular wearing plates 5 and 6, respectively. Outward of its wearing plate 6 the upper bearing member 3 is provided with a depending thrust flange 7. Radially disposed, conical bearing rollers 8 are interposed between the wearing plates 5 and 6, and their outer ends bear against a thrust ring 9 that is seated against the thrust flange 7 of the upper bearing member. The 45 thrust ring 9 is made circumferentially expandable and contractible by a transverse slit 10, and its periphery is slightly rounded in cross section and made to fit a correspondingly formed seat in the thrust flange 50 7, so that it will be held in position in

respect to the said thrust flange, by its own outward spring tension.

A retaining ring 11 is secured on the depending end of the hub 4 of the upper bearing member and underlaps the inner 60 edge of the lower wearing plate 5. Also, it will be noted that the lower wearing plate 5 underlaps the thrust ring 9. With this arrangement, therefore, the wearing plates 5 and 6 are interlocked to the upper bearing 65 member 3 and the rollers 8 and thrust ring 9 are caged between the said wearing plates, so that all of the said parts 5, 6, 8 and 9 are interlocked to the said upper bearing member. Of course this arrangement might 70 be reversed and all of the said members interlocked to the lower bearing member.

The arrangement illustrated in the drawings and described, is preferred for several good reasons, among which may be mentioned the facts that the illustrated construction provides an arrangement in which dirt and dust will work their way out from between the wearing plates, and rain, snow and dirt does not find a pocket in which to 75 accumulate on the lower wearing plate.

The retaining ring 11 may be locked to the hub 4 in various different ways, but preferably, as is shown, by an extremely simple, efficient and novel means best shown 80 in Figs. 2 and 3, and which described, is as follows: The said hub 4 has a reduced lower end provided with several, preferably two, diametrically opposite, outwardly projecting lock lugs 12, and the retaining ring 85 11 is provided with a lug clearing notch 13 formed by temporarily bending a lip 14 outward, as shown in Fig. 3. When this ring 11 is placed on the reduced end of the hub 4, above one of the lock lugs 12, and with its notch 13 alined with the other lug 12, the said ring may be easily moved into a horizontal plane above both of the lugs 12. As best shown in Fig. 2, the lip 14, being 90 turned back into the plane of the retaining ring 11, the said ring becomes interlocked to the said hub 4. When it is desired to move the retaining ring, the lip 14 must be bent back into the position shown in Fig. 3, 95 so as to open up the lug clearing notch 13, and this being done, the said retaining ring may be removed by reversing the process of its application.

The individual or intermediately formed 100 wearing plates 5 and 6 and thrust ring 9 105

make practical the use of cast steel bearing members having little or no finish, inasmuch as the load supporting surfaces and outer ends of the rollers have contact only 5 with the said members 5, 6 and 9, and these members being made from machine or tool steel, will be given the desired finish in the natural process of making the same from commercial sheets or other stock. Preferably, small and long bearing rollers are employed because these afford a greater number 10 of bearing points and less taper and resulting out-thrust on the rollers, and, furthermore, give a greater degree of rotation 15 to the rollers, which results in distributing the wear better on the rollers and reduces the tendency to flatten the same. Also, rollers of small diameter reduce the total height between the top and bottom of the 20 bearing plates, and this is important in many instances where space is limited. Furthermore, the arrangement described permits of ready and easy replacing or renewal of worn out bearing plates.

25 What I claim is:

1. In a center bearing, the combination with upper and lower bearing members and individually formed annular wearing plates applied thereto, of radially disposed rollers 30 interposed between said wearing plates, said bearing plates having hubs telescoped, one into the other, a retaining device applied to the outer of said hubs and immediately underlapping the inner portion of the adjacent 35 wearing plate, the bearing plate having the inner of said hubs being provided with a surface engaging the adjacent wearing plate, but terminated short of the inner edge thereof to afford clearance for said 40 retaining device.

2. In a center bearing, the combination with upper and lower bearing members, and individually formed wearing plates applied thereto, of radially disposed rollers interposed 45 between said wearing plates, means interlocking both of said wearing plates to one of said bearing members, with freedom for rotary movements of said wearing plates with their respective bearing members and 50 in respect to each other, and a thrust ring directly interposed between the outer portions of said wearing plates and engageable with the outer ends of said rollers.

3. The combination with upper and lower 55 bearing members, the former having a depending sleeve-like hub and a depending thrust flange, and the latter having an upwardly extended sleeve-like hub telescoped into the hub of said upper member, of in-

dividually formed annular wearing plates 60 loosely applied to said bearing members, radially disposed conical rollers interposed between said wearing plates, a thrust ring seated against the thrust flange of said upper bearing member and engaging the outer 65 ends of said rollers, and a retaining ring interlocked to the hub of said upper bearing member and immediately underlapping the inner edge of the lower wearing plate, and thereby interlocking the said wearing 70 plates and rollers to the upper bearing member.

4. The combination with upper and lower bearing members, the former having a depending sleeve-like hub and a depending 75 thrust flange, and the latter having an upwardly extended sleeve-like hub telescoped into the hub of said upper member, of individually formed annular wearing plates 80 loosely applied to said bearing members, radially disposed conical rollers interposed between said wearing plates, a retaining ring interlocked to the hub of said upper bearing member and immediately underlapping the inner edge of the lower wearing 85 plate, and thereby interlocking the said wearing plates and rollers to the upper bearing member, and an expansible thrust ring of said upper bearing member and engaging 90 the outer ends of said rollers.

5. The combination with upper and lower bearing members, the former having a depending sleeve-like hub and a depending thrust flange, and the latter having an upwardly extended sleeve-like hub telescoped 95 into the hub of said upper member, of individually formed annular wearing plates loosely applied to said bearing members, radially disposed conical rollers interposed 100 between said wearing plates, a retaining ring interlocked to the hub of said upper bearing member and immediately underlapping the inner edge of the lower wearing plate, and thereby interlocking the said 105 wearing plates and rollers to the upper bearing member, an expansible thrust ring spring seated against the thrust flange of said upper bearing member and engaging the outer ends of said rollers, the said thrust ring being caged between the outer portions 110 of said wearing plates.

In testimony whereof I affix my signature in presence of two witnesses.

LEE WARREN BARBER.
